(57) **CLAIM**

The ornamental design for a fluorescent lamp fixture, as shown and described.

DESCRIPTION

FIG. 1 is a perspective view of a fluorescent lamp fixture showing my new design;

FIG. 2 is a top plan view thereof;

FIG. 3 is a bottom plan view thereof;

FIG. 4 is a front elevational view thereof; and,

FIG. 5 is a side elevational view thereof, the opposite side being a mirror image.

The broken line showing is included for the purpose of illustration and forms no part of the claimed design.
